UNITED STATES PATENT OFFICE.

ARPÁD ANGYAL, OF BALHAM, LONDON, ENGLAND.

MEANS OF PLAYING PERCUSSION MUSICAL INSTRUMENTS.

Application filed December 16, 1925, Serial No. 75,829, and in Great Britain December 17, 1924.

The purpose of my invention is to introduce a novel construction of apparatus for playing percussion musical instruments other than pianofortes. An example of the type of instrument for which my invention is particularly adapted is the xylophone, which as is well known consists of a plurality of loosely supported pieces of wood each of which produces a particular tone of sound. However I wish it to be understood that my invention can be adapted for other instruments such as metal bars or tubes, bells, glass elements or other percussion devices except piano strings, or conversely other instruments can be adapted to my invention. My invention is so constructed that it may be played in the same manner as a piano, i. e. by the musician striking a keyboard, the keys of which when struck will transmit their movement to strikers contiguous to the instrument to be played.

According to my invention I provide a keyboard, as has heretofore been proposed for the same purpose, and a plurality of rods are connected to the keys and supported for axial rotation, each rod having connected to it a hammer or striker element for striking the notes of the instrument.

In carrying my invention into effect I provide a keyboard similar to that of a piano, and in juxtaposition to the keyboard are supported a plurality of metal rods corresponding in number to the number of keys on the keyboard. Each of these rods is so supported and connected to a key of the keyboard that axial rotation is imparted thereto whereby a striker or hammer carried by a cranked extension of the rod is caused to move towards the instrument to be played with consequent striking of one of the notes of the instrument.

In order that my invention may be clearly understood and readily carried into effect I have appended hereto a sheet of drawings illustrating an embodiment of same and wherein:

Fig. 1 is a front elevation.

Fig. 2 is a plan view, and

Fig. 3 is a sectional end view looking in the direction of the arrow A in Fig. 1.

Referring to the drawings I provide a suitable support 1 for the keyboard 2, and located in a horizontal plane slightly above the keys 3 and just in rear of same is a flat board or frame 5 upon which are supported a plurality of metal rods 6 flat upon

the board each rod being held in position in a suitable manner so as to be capable of being rotated axially. One convenient means of support for the rods comprises a number of pins 7 driven into the said flat board or frame 5. These pins if desired may be V or L shaped so as to engage over the rods. However any other suitable means may be employed for this purpose. Each rod is cranked at both ends, the end nearer the keyboard having an eye 8 at its extremity to which is pivotally connected a short, vertical link 9 the lower end of which is pivotally connected to a key on the keyboard, whereby depression of the key will result in a pull being effected on the cranked end of the rod above the key with consequent axial rotation of the rod. The links 9 are preferably of flexible material, for instance cord or flexible wire. The other end of the rod is cranked in an opposite direction as at 7 and carries a hammer or striker 10 so that depression of the key will result in the hammer being raised, and immediately upon the musician releasing the key the hammer will return at once to its normal position under the influence of its own weight. Felt or other suitable material 11 is preferably interposed between the rods 6 and the board 85 or frame.

The rods 6 preferably radiate outwards somewhat symmetrically from the keyboard, but of course the degree of radiation will have to be varied, according to the size of 90 musical instrument it is desired to play. The musical instrument 12 to be played is supported in a horizontal plane above the hammers or strikers, and for this purpose raised ledges 13 or other suitable means of 95 support are provided at the ends of the flat board or frame supporting the rods.

The keys of the keyboard are preferably fulcrumed on a common axis 14 about their median position, but have their portions 15 which do not constitute the actual keyboard heavier than the key portions so that an immediate return to normal position of the keys is ensured, irrespective of the weight of the hammers or strikers which also assist 105 in the return of the keys.

The hammers or strikers will be varied in material or construction according to the type of instrument to be played, but a form of hammer suitable for most instruments 110 for which my invention is intended and particularly for the playing of the xylophone,

comprises a vertical metal cylinder 16, solid or loaded with lead or other substance of a high specific gravity, and the top of the cylinder carries a cap or plug 17 of leather, fibre, wood or other desired material for striking the note.

If desired means may be provided to enable the volume of sound produced to be muffled or reduced. One suitable means of 10 effecting this is to provide a horizontal bar close to the hammers or strikers and carrying along one edge a strip of fabric, rubber or other suitable material. This bar may for instance be a movable bar substituted 15 for the bar 18 carrying felt 11 such bar being shown as a fixture in the drawings. By moving this bar towards the hammers the strip of fabric becomes interposed between the strikers or hammers and the notes 20 of the instrument to be played so that a muffled effect is produced. The bar may be moved by hand, but it is preferred to operate it by a foot pedal similarly to a piano 25 pedal, and for this purpose a cable or cord connects the pedal to the muffle bar and springs are provided to maintain and return the said bar to normal position.

Strips of felt or other suitable material 19 are provided for supporting the sound 30 producing members 20 to be struck, a suitable method of supporting these members, which may be in the form of bars or the like being shown in the drawings, as comprising a number of eyeleted pins 21 passed 35 through holes 22 in the members, a length

of catgut or other suitable material being passed through the eyes of the pins. The front ends of the members can be supported in a similar manner, the pins however not passing through the members.

A number of inverted hollow box like members 23 of wood or other suitable material may be provided over the members 20, one box like member being located over each member 20, the dimensions of the boxes varying according to the tones of said members. By this manner extra resonance can be obtained.

An apparatus constructed according to my invention will be cheap to produce so as to 50 be within the means of most people.

What I claim is:—

In apparatus for playing percussion musical instruments, a keyboard including a depressible key, a member to be struck to sound a note, a frame member, a rod mounted on said frame member for axial rotation, a crank at each end of said rod, a flexible connection between the crank at one end of said rod and said key whereby depression of said key imparts rotation to said rod, and a hammer member carried by the crank at the other end of said rod normally spaced from said member to be struck and movable into striking engagement with said member by rotation of said rod upon depression of said key.

In witness whereof I have signed this specification.

ÁRPÁD ANGYAL.
